UNITED STATES PATENT OFFICE.

JERVIS B. WEBB, OF DETROIT, MICHIGAN.

CONVEYER.

Application filed February 12, 1925. Serial No. 8,608.

My invention relates to conveyers comprising endless conveyer means, and it has for its general object to provide a construction of this character comprising an improved and novel construction of means for supporting intermediate portions of the conveyer.

It is also an object of the invention to provide a conveyer having an improved and novel construction of means at intervals for supporting the loads adapted to be transported by the conveyer from one point to another.

Another object of the invention is to provide a conveyer of novel construction, including means whereby the durability of the conveyer is increased.

Another object of the invention is to provide a construction of conveyer in which novelty and simplicity are combined in a manner to produce a construction of great efficiency.

Other objects and advantages of the invention will be pointed out in the detail description thereof which follows, or will be apparent from such description.

In order that the invention may be readily understood and its practical advantages fully appreciated, reference may be had to the accompanying drawings, in which I have illustrated certain forms of convenient embodiments thereof. However, it will be understood that changes in the details of construction may be made within the scope of the claims without departing from the invention.

In the drawings,—

Fig. 1 is a view in transverse section of a conveyer structure embodying the invention;

Fig. 2 is a view taken on the line 2—2 of Fig. 1;

Fig. 3 is a perspective view showing a detail of the structure;

Fig. 4 is a view in side elevation of a portion of the structure, and in which an object which is being transported thereby is indicated in dash and dot lines;

Fig. 5 is a transverse sectional view showing a modified construction of conveyer structure;

Fig. 6 is a sectional view taken on the line 6—6 of Fig. 5;

Fig. 7 is a top plan view of a fragmentary portion of the structure showing a detail of construction;

Fig. 8 is a perspective view of an element of the construction; and

Fig. 9 is a view in side elevation of a portion of the conveyer structure shown in Fig. 5.

Referring to the drawings, it will be noted that the frame structure of the apparatus comprises cross-wise extending members 1 arranged at intervals. These members in the construction as illustrated consist of angle plates, but it will be understood that other shapes may be employed. Posts or standards 2 of angle members, or members of other shapes, are secured at their lower ends by means of rivets 3 to the opposite ends of the cross-wise extending members 1 and extend upwardly therefrom. These are connected intermediate their ends by cross-wise extending bars 4 of channel shape, but bars of any other shape in cross section may be employed. The upright posts or standards 2, which are located at intervals on opposite sides of the structure, are also connected by longitudinally extending plates 5.

Referring now to Figs. 1 to 4, inclusive, it will be observed that angle members 6 and 7 are secured by means of rivets 8 to the upper ends of the posts or standards 2, and that the said angle members extend longitudinally of the structure at substantially right angles to the cross members 1 and 4. One flange of each of the angle members 6 and 7 occupies a vertical position, the flange 7 overlying the flange 6. The other flange of each of the said members extends inwardly as indicated at 9 and 10. These flanges are spaced from each other, as indicated in Fig. 1 of the drawings. The flange 10 of each angle is provided with notches or openings 12 at intervals for a purpose to be hereinafter referred to. In addition to the angle members 6 and 7, angle members 15 are secured to the tops of the posts or standards 2 with the horizontal flanges 16 thereof in the same plane as the horizontal flanges 9 of the angle plate 7. The flanges 16 and 9 operate to form a platform structure at the opposite sides of the conveyer structure. The vertical flanges 17 of the angle members 15 constitute and form outer sides of the platform formed by the horizontally extending flanges 9 and 16.

Conveyer chains 20 located at the opposite sides of the structure are driven or operated by any suitable means (not shown).

The upper portions or sections of these chains occupy positions between the inwardly extending flanges 9 and 10. Shafts 22 are supported at intervals upon these chains. 5 Their opposite ends are mounted rotatably in bearings supported at intervals upon the chains 20. These bearings consist of complementary members 23, each of which is provided with a projection 25 which is adapted 10 to project into the openings of alternate links of the chains, as is clearly shown in the drawings. These members are provided with openings 26 which extend therethrough, and through which the opposite 15 ends of the shafts 22 extend. Each of the shafts is provided with collars 27 which are secured thereto near the opposite ends thereof in adjacent relation to the inner members of the bearings 23. Nuts 29 upon the opposite 20 ends of the shafts engage the outer members of the bearings so that the members 23 of said bearings are clamped between nuts 29 and collars 27. It will be seen that in this way each of the shafts 22 25 is connected with the conveyer chains at the opposite sides of the structure, and that thereby the said chains are bound together to form a unitary conveyer structure.

Cylindrical load supporting members 30 30 are mounted upon the shafts 22. In the construction as shown these load supporting members 30 are tubular or hollow for the sake of lightness, but it will be understood that, if preferred, these cylindrical members 35 may be solid. The upper portions or sections of the chains 20 are supported upon the supporting rollers 31 mounted near the opposite ends of shafts 32. The rollers 31 are rotatable upon the shafts 32, or, if preferred, 40 the shafts themselves may be rotatably mounted in their bearings. The rollers 31 are held in place upon the shafts 32 by means of collars 33 mounted upon the opposite end portions of the shafts in spaced relation to each other.

The opposite ends of certain of the shafts 32 are supported in the upright posts or standards 2, while others thereof are supported in brackets 35 which are secured to 45 and depend from the upright flanges of the angle members 6 and 7. The rollers 31 project upwardly through the openings 12 in the horizontal flanges of the angle members 6 so that the upper horizontal portions or 50 sections of the conveyer chains are adapted to be supported thereby. Said portions are also supported upon the upper sides of the horizontal portions 10 of the angle members 6.

55 For supporting the lower horizontal portions of the conveyer chains I have provided tracks 40 supported upon the upper edges of the cross bars 1. The cylindrical load supporting members 30 rest upon the upper 60 sides or edges of these tracks and through the shafts 22 the horizontal portions of the conveyer chains are supported. As already indicated, the shafts 22 are rotatably supported in their bearings at their opposite ends, which bearings are carried by the chains 20. When the shafts 22 and the load supporting means 30 thereon are in the upper part of the structure, in which position the upper portions or sections of the chains 20 are supported upon the rollers 31, 70 the said shafts and load supporting means do not rotate, but when in the opposite position, with the load supporting means 30 resting upon the tracks 40, rotation of said load supporting means and the shafts 22 is effected. Such rotation facilitates the linear traveling movement of the conveyer chains and reduces the friction which is necessary to be overcome by the power means by which the chains are driven.

The load 41, shown in dash and dot lines in Fig. 4 of the drawings, is supported upon a plurality of adjacent load supporting members 30 and may be transported thereby from one position to another.

Referring now to Figs. 5 to 9, inclusive, of the drawings, it will be noted that the upper ends of the posts or standards 2 are connected together by the vertical flanges 44 of the longitudinally extending angle members 45. The horizontal flanges 46 extend inwardly and overlie the upper portions or sections of the chains 20. Channel bars 47 extend between the chains 20. The flanges of said channel bars extend outwardly, as indicated in Figs. 5 and 6 of the drawings, and the opposite ends thereof, which are reduced as indicated at 48, extend through alternate links of the conveyer chains. The inner sides of the links through which the opposite ends of the channel members 47 extend contact with shoulders 50. Retaining filler blocks 51 are secured by rivets 52 to the opposite ends of the channel members between the flanges thereof. The inner ends 100 of these filler blocks are provided with outwardly extending projections 53, which contact with the outer sides of the links of the chain through which the opposite ends of the channel members extend. Each of the 105 channel members 47 is provided with upwardly extending angular supporting members 55. These supporting members are secured to the flanges of the angle members 110 and are arranged in couples near the opposite ends of the channel members. At their upper ends these angular supporting members are provided respectively with outwardly extending portions 56, to which the load supporting platforms 57 are secured by 115 rivets 58. These load supporting platforms extend transversely of the structure with their opposite ends located in adjacent relation to the inner edges of the horizontal flanges 46 of the angle members 45. The 120

front and rear portions of these load supporting platforms 57 are inclined inwardly; that is, toward the plane of the chains by which they are supported, as is indicated at 60. The objects to be transported are supported upon the central horizontal portions of the platforms 57. The presence of the inclined portions 60 prevents the falling of the load from a platform in case it should 10 become displaced from the central horizontal portion thereof.

The upper portions or sections of the chains 20^a are supported upon rollers or wheels 31^a mounted upon shafts 32^a, certain 15 of which are supported at their opposite ends in oppositely disposed posts or standards 2, while others thereof are supported in depending bracket plates 35^a. These depending bracket plates 35^a are secured at intervals to the vertical flanges 44 of the angle members 45.

The lower portions or sections of the conveyer chains 20^a are supported upon rollers or wheels 61 rotatably mounted near the 25 opposite ends of shafts 62, supported at their opposite ends in the longitudinally extending plates 5. The wheels 61 are retained in place by means of the collars 63, located upon the opposite sides thereof, and secured to the shafts 62. Instead of the rollers or 30 wheels 61 being rotatably mounted on the shafts 62, they may be rigidly secured thereto, in which case the shafts 62 should be rotatably mounted upon the supporting plates 35. If preferred, not only may the shafts 62 be rotatably mounted, but the rollers or 35 wheels 61 may also be rotatably mounted upon the said shafts.

Secured at intervals to the vertical 40 flanges 44 of the angle members 45 are angle clips or brackets 64, upon which the horizontal flanges 65 of angle members 66 are supported. The vertical flanges 67 of these 45 angle members constitute guards for the platform formed by the horizontal flanges 46 and 65.

The conveyer chains 20^a may be driven by any suitable power means (not shown).

The conveyer structures as illustrated and 50 described are designed primarily for transporting molds employed in connection with

the manufacture of vehicle tires from one point to another in the factory where they are manufactured, but it will be understood that the conveyers illustrated may be employed for conveying other objects from one point to another.

It will be seen that by my invention I have provided a simple and durable construction of conveyer apparatus, by the employment 60 of which objects may be transported most efficiently and conveniently from one point to another.

Having thus described my invention, what I claim and desire to secure by Letters Patent is:

1. In conveyer apparatus, the combination of flexible endless conveyer means located in parallel spaced relation to each other, rotatable bars extending transversely of and connected at their opposite ends to the said conveyer means, which bars are adapted to support loads to be transported by the said conveyer means, combined stationary and rotatable supporting means for supporting 70 the upper portions of the said flexible conveyers, and means for supporting the said load supporting means and the said conveyer means when the latter occupy their lower position.

2. In conveyer apparatus, the combination of endless conveyer chains, stationary means located underneath the upper portions of the said conveyer chains for supporting the same, rotatable supplemental supporting means located at intervals underneath the upper portions of said conveyer chains and projecting slightly above the planes of the upper surfaces of the said stationary supporting means, means for supporting the 80 lower portions of said conveyer chains, and load supporting means located at intervals and extending transversely of said conveyer chains and the respective means being connected at their opposite ends to and supported by the said chains, substantially as described.

In testimony that I claim the foregoing as my invention I have hereunto signed my name this ninth day of February, A. D. 100 1925.

JERVIS B. WEBB.
